Des. 212,162
Patented Sept. 3, 1968

212,162

COMBINED PLANTER, ROOM DIVIDER, SUN LAMP AND SPEAKER UNIT

Gregory R. Davis, 6725 S. Eberhart Ave.,
Chicago, Ill. 60637

Filed Aug. 18, 1967, Ser. No. 8,314

Term of patent 14 years

(Cl. D33—1)

FIG. 1.

FIG. 2.

FIG. 3.

FIG. 4.

FIG. 1 is a perspective view of a combined planter, room divider, sun lamp and speaker unit showing my new design from the front and right side;

FIG. 2 is a top plan view of the divider;

FIG. 3 is a perspective view of the divider from below and the left side; and

FIG. 4 is a side elevation of the divider.

I claim:

The ornamental design for a combined planter, room divider, sun lamp and speaker unit, as shown.
